Primary Examiner—James M. Gandy
Attorney, Agent, or Firm—James D. Hall

[57] CLAIM

The ornamental design for an automotive console ice chest and cooler, as shown and described.

DESCRIPTION

FIG. 1 is a perspective view of the automotive console ice chest and cooler showing my new design;

FIG. 2 is an enlarged side elevational view thereof;

FIG. 3 is an enlarged front end elevational view thereof;

FIG. 4 is an enlarged rear end elevational view thereof; and

FIG. 5 is an enlarged top plan view thereof.

The bottom of the automotive console ice chest and cooler is flat and unornamented.
